[57] CLAIM

The ornamental design for the clamp for portable light or similar article, substantially as shown and described.

DESCRIPTION

FIG. 1 is a top, right end perspective view of a clamp for portable light or similar article showing my new design.

FIG. 2 is a top, left end perspective view thereof on an enlarged scale.

FIG. 3 is a bottom perspective view thereof.

FIG. 4 is a top view thereof.

FIG. 5 is a side elevational view thereof.

FIG. 6 is a bottom view thereof.

FIG. 7 is a left end elevational view thereof.

FIG. 8 is a right end elevational view thereof.

The support and light are shown in broken lines for illustrative purposes only.

FIG. 1

FIG. 3

FIG. 2
